United States Patent Office.

MELTIER NYE AND ABRAHAM J. KNISELY, OF CHICAGO, ILLINOIS.

Letters Patent No. 74,765, dated February 25, 1868.

IMPROVED BRICK-MACHINE.

The Schedule referred to in these Letters Patent and making part of the same.

TO WHOM IT MAY CONCERN:

Be it known that we, MELTIER NYE and ABRAHAM J. KNISELY, of the city of Chicago, and State of Illinois, have invented new and useful Improvements in Brick-Machines; and we do hereby declare that the following is a full, clear, and exact description of the same, reference being had to the accompanying drawings, and to the figures and letters of reference marked thereon, in which—

Figure 1 is a front elevation.

Figure 2 is a side elevation.

Figure 3 is side view of a spring and valve placed in front of receiving-box U.

Figure 4 is a front view of the same spring and valves.

Figure 5 is one view of a weight and lever to control the yielding fulcrum-block F, shown in fig. 2.

Figure 6 is another arrangement of levers and weight, shown in fig. 2.

Figure 7 is another arrangement of the lever E, shown in fig. 2, and method of governing it.

To enable others skilled in the art to make and use our invention, we will proceed to describe its construction, and operation.

The nature and object of our invention are to construct a brick-machine, simple in its form, construction, and operation, and to be worked by any power desired.

Our machine is made of the height and breadth desired, and can be made in circular or square form. We prefer to make it in the square form. It is made of framework, and lined or sided up with plank of the requisite thickness on the inside, leaving the framework outside of the plank-work.

Similar letters of reference refer to similar parts in the different figures.

A, figs. 1 and 2, is a shaft, passing down through the centre of the machine, and is provided with arms and a screw to agitate the clay and force it downwards. B is a bevel-wheel attached to the shaft A. C is a bevel-wheel smaller than B, attached to the shaft a. C' is another wheel of the same size as C, attached to the shaft a'. D is a crank attached to and working from the shaft a, provided with a pin, D', fig. 1. E is a vibratory lever working on the fulcrum E', which is attached to the movable or yielding fulcrum-block F. N is a lever attached at its lower end to the shaft N'' at N'. M is a connection, uniting the levers N and E. R is a chain attached to the lever N, at or near its upper end passing over the sheave T, and is attached to the weight S at its other end. H is a right-angled lever working upon its fulcrum H' located at the angle of the lever. G is a connecting-rod, connecting the movable or yielding fulcrum-block F with the short arm of the right-angled lever H, at the pivot G'. Y is a weight, connected to the long arm of the right-angled lever H by the chain I. K is an arm extending from the top of the frame of the machine. J is a rod, extending from the end of the long arm of the right-angled lever H, up through the extended end of the arm K, terminating in a screw, and upon which works the nut L'. L is a rubber washer, placed under the nut L' on the rod J. The rod J freely moves through the arm K. U is a receiving-box, located in front of the machine, and upon the table Q. The table Q extends out in front of the machine, and back under the machine about one-half its width. e e, fig. 1, is a plunger, working in the receiving-box U. b, fig. 1, is a rod, connected at its lower end b' to the plunger e e, and at its upper end to the crank-wheel x, attached to the shaft a. d d are guide-rods attached to the plunger e e. i is a standard, fastened at the upper part of the front side of the receiving-box U. f is a spring, attached at one end to the upper end of the standard i; at k. There is a series of these standards i and springs f, as shown in fig. 1. N'' is a shaft passing across the machine at or near the lower end. O O are levers extending from the shaft N'' up through the table Q. The table Q is provided with slots for the levers O O to work in. P is a rolling-shaft extending from one lever O to the other lever O. g, fig. 3, is a hinged valve, hung before the receiving-box U, at or near its lower edge; these valves cover openings in the receiving-box U. There is a series of these valves. The valves g are made with two ears, t t, extending from the upper edge, one on each side. A recess is made at each side of the valve-openings in which they are inserted. The pins h h pass down in front of these ears, and thus the valves are held in position, and admit of the valves working on these ears.

The operation of our invention is as follows: Power is applied to the shaft A in any way desired; motion is thus communicated to the wheels C and C'. The clay is forced down into the receiving-box U. The moulds to

receive the clay are placed under the machine on the table Q, in front of the rolling-shaft P. The clay is forced down into the moulds by the plunger e e, by means of the rod b and crank-wheel x. As the crank D revolves, at each of its revolutions, the pin D' comes in contact with the upper end of the vibratory lever E, which working on the fulcrum E', the other end moves in an opposite direction, causing the lever N, by means of the connection M, to move in the same direction. This partially revolves the shaft N'', and causes the levers O O, with the connection M, to move forward, which in turn shoves the empty moulds forward under the receiving-box U, shoving the already filled mould out from under the receiving-box U on the table Q, before which the workman stands with strike in hand, and strikes the upper surface of the bricks smooth. As the lever N moves forward, the weight S is raised, and when the crank D relieves the lever E, the weight S brings the system of levers back to their proper position.

It frequently happens that stone and other obstacles will get into the machine, and are forced down into the receiving-box U, and thus forced into the moulds, and unless there is a yielding point somewhere between the crank D and the stone or obstacle wedged in the mould, there would be a breakage somewhere. This is obviated by the use of the movable fulcrum-block F. Whenever the moulds are arrested in passing out from under the receiving-box U, the fulcrum-block F will yield and allow the lever E to move, so as to allow the crank E to pass on.

By means of the right-angled lever H, the weight Y, and rod J, the movable fulcrum F is kept at one point in the slot, in which it moves up to a certain degree of resistance, which is regulated by increasing or decreasing the weight Y; and by adjusting the rod J by means of the nut L', the movable fulcrum-block F is kept at any point desired in the slot in which it moves. This governing of the movable fulcrum-block F regulates the distance the rolling-shaft P shoves the moulds under the receiving-box U.

Whenever a stone or other obstacle gets into the mould of a larger size than a brick, and thus prevents the moulds from passing out from in under the receiving-box U, the movable fulcrum-block F will yield and allow the crank D to pass by the end of the lever E, while the rolling-bar P, which shoves the moulds out from in under the receiving-box U, remains stationary, and thus the machine sustains no injury. As the fulcrum-block F moves backward, the weight Y and rod J are raised, and when they return to their proper position, the cushion is relieved by the rubber washer L.

It frequently happens that a stone of a smaller size will find its way into the moulds sufficiently large to wedge the moulds in under the receiving-box U. Any injury that might arise from this is obviated by the use of the hinged valves g and spring f. As the mould is shoved out, the springs f yield, and take the position of the dotted lines f', and the valve takes the position of the dotted lines g'. The mould and the stone are thus permitted to pass out, the machine in no respect sustaining any injury, or the operators loss of time. Whenever it is desired to remove the stone or obstacle before the hinged valve g, the lower end of the spring f is turned to one side, as shown by the dotted lines f'', fig. 4, the upper ends of these springs being loosely attached at k to admit of this side movement.

The springs f press against the valves g, with sufficient force to enable the valves to resist the ordinary pressure of the clay. There are as many of these valves and springs as there are bricks in a mould. The moulds are placed under the machine on the table Q, back of the receiving-box U, from an opening on the left of the machine. This opening is shown at Z, fig. 1, the post of the machine being cut away to enable the moulds to pass out.

We do not confine ourselves to the specific device shown in fig. 2, for governing the movable fulcrum-block F. There are other methods for doing it. The right-angled lever H can be turned around and a weight attached to the end, as shown at n, fig. 5; V being the weight and the method of applying it.

Fig. 6 shows another method of governing this same fulcrum. The lever H and its weight are dispensed with, and a spiral spring is inserted in the slot at one side of the fulcrum.

Fig. 7 shows another form of the lever E. The lever is hinged at p, just below the fulcrum E', the movable fulcrum-block F being dispensed with. A spring, q, is attached to the upper part of the lever E'', and extending down, works in a loop, r, attached to the lower part of the lever. The spring q is strong enough to work the two parts E'' and E''' of the lever E, as a whole, until some obstacle intervenes to prevent the moulds from passing out from in under the receiving-box U. When the part E'' becomes stationary, the part E''' moves upon its hinge p, and crank D is permitted to pass, when the spring q causes the part E''' to return to its original position; thus the machine sustains no injury. The plunger b and the crank D move relatively. The crank D passes the lever E just as the plunger is in the act of rising. This relative movement is accomplished by properly adjusting the cranks x and D.

In figs. 5 and 6, the movable fulcrum is adjusted to any desired point in the slot in which it moves by means of the set-screw m.

Having thus described our invention, what we claim as new, and desire to secure by Letters Patent, is—

1. The combination of the movable fulcrum F, connecting-levers E, M, and N, with rolling-shaft P, chain R, and weight S, substantially as and for the purpose shown.

2. In combination with the movable fulcrum F, we claim the connecting-rod G, lever H, chain I, weight y, and rod j, substantially as and for the purpose shown.

3. Combining the adjustable pivoted springs f with the hinged valves g, substantially as and for the purpose herein shown and described.

MELTIER NYE,
ABRAHAM J. KNISELY.
